CRANK CASE CLEANER AND HUMIDIFIER

Filed Oct. 5, 1927

UNITED STATES PATENT OFFICE

HERBERT A. HAWES, OF COLDWATER, MICHIGAN

CRANK-CASE CLEANER AND HUMIDIFIER

Application filed October 5, 1927. Serial No. 224,157.

The object of the invention is to provide a simple and efficient attachment which will utilize vapor from the radiator of an automobile for charge moistening purposes and which will also create a partial vacuum in the crank case and withdraw any gasoline vapors therefrom and tend to retain the lubricant within the crank case and also on the engine pistons.

10 It is an object broadly to improve the humidifier in a gasoline engine also to improve the crank case construction whether it is done by a simple attachment or otherwise.

15 Further objects and objects pertaining to details and economies of construction definitely appear from a detailed description to follow. I accomplish the objects of my invention by the devices clearly described in 20 the following specification.

The invention is clearly pointed out and described in the claims.

A preferred embodiment of my invention is fully illustrated in the accompanying 25 drawing forming a part of this specification, in which:

Fig. 1 is a detailed perspective view in broken section with hood and part of the frame broken away of an automobile embodying my invention with my improved attachment installed.

Fig. 2 is a vertical detail sectional view through the valve control casing and means partially in section and partially in full lines, 35 same being a vertical section on a plane through connection 81.

Fig. 3 is an enlarged detail vertical sectional view through the intake connection to my device taken on the plane of line 3—3 of 40 Fig. 1.

Fig. 4 is a detail view of my improvement partially in section showing an adapter for attaching the same to breather pipes or oil intake pipes of a smaller size than the device.

45 The parts will be identified by their numerals of reference which are the same in all views.

1 is the engine, 2 is the intake manifold, 3 is the crank case, 4 is the breather pipe or oil intake of the usual form, 5 is the radiator,

51 is the radiator cap which must fit airtight, 52 is the radiator overflow pipe. These are all in the usual form.

6 is the casing of my improved control valve structure having a diaphragm 62 there-across and a downwardly projecting flange 621 which extends into and fits in the top of the breather pipe 4 after the breather pipe cap has been removed. A hard felt washer 61 is interposed to make a tight joint. A 60 valve port 63 is in the center of the diaphragm 62 and is controlled preferably by a flat valve 64 having stem 641 which is surrounded by a spring 65 which is held in place by a projecting lug or pintle 66 in the top of the 65 shell 6.

7 is an airtight connection pipe connected to the bottom end of the overflow pipe 52 and passed through the side of the breather 4 at a point a little below the lower end of the 70 flange 621. 71 is the elbow connection for pipe 7 and is provided with screen 72.

8 is the suction pipe connected at 81 to the upper part of the valve casing 6 and extending to connection 82 where it connects to the 75 intake manifold 2. This may be connected in connection with the exhaust pipe 9 of the vacuum feed system, if one is made use of on the engine.

I have shown the vacuum feed exhaust 9 in 80 the usual form.

I have illustrated my device as applied to the usual construction of Ford car. The control valve casing 6 is put in place of the cap of the breather or oil intake pipe. On makes 85 of car where the oil intake pipe is small, as at 40 in Fig. 4, I provide an adapter 60 which has a downwardly extending shank or tube 602 and is provided with a felt washer 601 for insertion into such smaller oil intake or 90 breather pipe. The upper end of the adapter 60 is of the correct size and dimension to receive the control valve case 6.

It will be observed at each stroke of the engine, the pipe 8, owing to its connection, will 95 be partially exhausted and the air and vapor from casing 6 will be sucked in up through the breather past the valve 64 into the engine.

The valve 64 acts as a check valve and because suction is created and vapor arises in 100

the upper part of the radiator, the said vapor will be at once exhausted down into the crank case, passing just beneath the diaphragm 62. A considerable suction is created and a partial vacuum is created in the crank case. This has a tendency to draw all oil tending to escape back into the crank case thus avoiding a leakage and waste of oil in that manner and also tending to prevent the tendency of the oil to rush into the engine cylinder. Any slight amount of gasoline or charge that leaks into the crank case will be at once vaporized and drawn past the valve 64 back into the engine intake manifold where it will be utilized in the charge. Thus there is a saving of any gasoline that escapes past the piston into the crank case. The oil is maintained in position and a very desirable amount of moisture is constantly delivered into the charge in vaporized condition. No heavy particles of water can pass in because the screen 72, in addition to its function as a screen, breaks that up. This structure operates very simply by the connection to the cap on the breather pipe to create a partial vacuum in the crank case, the vapor delivering from the radiator below the point of suction where the vapor will be drawn together with the air and evaporated oil and gasoline from the crank case. This will be delivered centrally to the intake manifold where it will be distributed to add a proper moisture content to the entire charge thus greatly improving the same and adding to the efficiency of the engine and at the same time avoiding accumulations of carbon.

I desire to claim my invention broadly and I also desire to claim the specific attachment by which the thing is accomplished as pointed out in the appended claims.

Having thus described my invention what I claim as new and desire to secure by Letters Patent is:

1. The combination of a gasoline engine having the usual construction of engine cylinder and manifold intake, crank case, breather pipe and radiator with overflow pipe, a connection from the lower end of the overflow from the radiator to the crank case at the breather pipe to withdraw vapor and create partial vacuum, a control valve case with suitable flange and packing for attachment to the top of the breather pipe, an apertured diaphragm within the same and a spring seated check valve closing the aperture in the said diaphragm, a suction pipe connection from the control valve casing to the intake manifold of the said engine all coacting substantially as described.

2. In a radiator water cooled gasoline engine the combination having a suction connection from the intake manifold to the crank case creating a partial vacuum therein, a control valve chamber with a check valve therein interposed in the said suction connection, a connection from the enclosed air chamber of

the radiator to the crank case delivering at a point in proximity to the said check valve, as specified.

In witness whereof I have hereunto set my hand.

HERBERT A. HAWES.
